[57] CLAIM

The ornamental design for a bicycle fender reflector, substantially as shown and described.

DESCRIPTION

FIG. 1 is a side elevational view of a bicycle fender reflector showing our new design, a portion of a bicycle fender being shown in broken lines for illustrative purposes only;

FIG. 2 is a rear elevational view thereof on an enlarged scale;

FIG. 3 is an elevational view on an enlarged scale of the side opposite that shown in FIG. 1;

FIG. 4 is a front elevational view thereof on an enlarged scale; and

FIGS. 5 and 6 are respectively top and bottom views thereof on an enlarged scale.
